(57) **CLAIM**

I claim the ornamental design for a snorkel, as shown and described.

DESCRIPTION

FIG. 1 is a right side, rear perspective view of a snorkel illustrated as being attached to a right side of a vehicle, FIG. 2 is a front right side perspective view of the snorkel of FIG. 1,

FIG. 3 is a front left side perspective view of the snorkel of FIG. 1,

FIG. 4 is a left side view of the snorkel of FIG. 1,

FIG. 5 is a right side view of the snorkel of FIG. 1,

FIG. 6 is a top view of the snorkel of FIG. 1,

FIG. 7 is a bottom view of the snorkel of FIG. 1,

FIG. 8 is a rear view of the snorkel of FIG. 1; and,

FIG. 9 is a front view of the snorkel of FIG. 1.

All broken lines illustrate portions of the snorkel to which the design is applied that form no part of the claim.
